UNITED STATES PATENT OFFICE

2,606,761

HYDRAULIC DOOR ACTUATOR

Charles G. G. Group, Cleveland, Ohio

Application June 29, 1949, Serial No. 102,070

1 Claim. (Cl. 268—37)

1

This invention relates to door openers and more particularly to a door opener hydraulically operated by a weight on a platform.

The desirability for an automatic door opener has long been present. Among the first attempts to fill this need is the gate which opens upon pulling a rope on the end of a long lever. Since that time, many more attempts have been made with more or less success. These attempts include those openers which require electronic circuits for their action. These may be set off either by sound, as from a tuned horn or by the interruption of a light beam focused on a photoelectric cell. These, however, require an electronic relay and a motor and are, therefore, somewhat expensive and are subject to tube failures and the like in the relay.

Other attempts have been based on hydraulic mechanism. In order to obtain pressure for these systems, it was common to use the pressure of city water or that supplied by a separate pump. This gave an adequate supply of fluid to operate the actuator piston through its relatively long required stroke. In general, however, these required the manual turning of a valve which was mounted on a post beside the driveway, requiring that the automobile be run sufficiently close to that valve to reach it, or that the driver disembark which is the maneuver sought to be avoided.

The principal reason for the lack of a simple door opener operated by the weight of the vehicle approaching the door has been the fact that a long stroke is required of the operating piston, and this piston must be of sufficient area to supply force enough to start the opening of the door even when it sticks somewhat. This requires a fairly large quantity of oil or other hydraulic fluid, and in order to obtain this volume, the pressure generating cylinder must be sufficiently large to deliver the full quantity. However, this leads to a severe problem. The volume must be obtained either by lengthening the stroke or increasing the diameter. Lengthening the stroke, in general, leads to a situation where the car must be tilted uncomfortably to operate the device. Increasing the piston diameter on the other hand decreases the available pressure for a given weight to the point where the force of the actuator piston may be insufficient to overcome the dead weight or a little stickiness in the door.

By my invention, I provide a means whereby this initial inertia and stickiness is overcome by a high starting pressure and after the door is

2

started opening, sufficient volume of fluid is supplied at a lower pressure to continue the opening of the door.

A more complete understanding of my invention, and the invention itself, may be had from reference to the accompanying figures in which:

Fig. 1 is a view partly in section showing the actuator of my invention;

Fig. 2 is a front view of the pressure supply mechanism of my invention showing the pressure cylinders in section;

Fig. 3 is a side view of the pressure supply system;

Fig. 4 is a side view of an alternative embodiment of my pressure supply system;

Fig. 5 is a sectional view showing another alternative form of the pressure supply system of my invention;

Fig. 6 is a view similar to Fig. 5 showing still another alternative form of the pressure supply system of my invention;

Fig. 7 is a view showing my invention as applied to one type of gate;

Fig. 8 is a sectional view showing my invention as applied to a tilting door; and

Fig. 9 is a section view from above the door showing the mounting means.

Briefly, my invention comprises an actuating cylinder which may be adapted to operate any of several well known types of doors. In the main, these doors are cable operated, and therefore I have shown the device as adapted to wind a cable on a drum. It will be apparent, however, that my invention need not be so limited. The fluid under pressure for this cylinder is supplied from a plurality of pressure cylinders. In the simplest form, there are two cylinders engaged by a platform over which the vehicle is driven. These would be arranged so that the platform would engage one some time before engaging the other. Since the full weight on the wheel then on the platform is first applied to a single piston, the pressure will be quite great at first. As the platform engages the second piston, since the weight will then be divided between the two, i. e., over twice the piston area if the pistons are of equal size, the pressure then is halved. However, since the door has already been started by the high pressure, less pressure is required to continue the opening process and the required volume is obtained by the use of the two cylinders. Several variations of this device are shown in the figures and more fully described below.

The actuator cylinder of my device is best shown in Fig. 1 with its mounting and the drum

for connection to cable operated gates or doors. The cylinder 11 is mounted on a plate 12 which is adapted to be fastened to the wall of the building or gate post. A cable 13 extends from the rod 14 of the piston 15 around a pulley 16 also pivotally mounted on the plate 12. This pulley carries a drum 17 preferably of larger diameter than the pulley, on which the operating cables 18 of the door may be wound. From the pulley 16 the cable 13 passes to a point where it is fastened to a spring 19 adapted to keep tension in the cable and to return the piston 15 to its top position in the cylinder 11 when the fluid pressure is released.

A simple valve system may be used in this cylinder to provide for relatively quick opening and slow closing action. The main fluid supply line 21 leads into the cylinder through a check valve 22. This valve may be of any usual type, it being shown diagrammatically for the purpose of this description. This valve 22 allows the fluid to enter the cylinder freely, but when the pressure is released, the valve closes causing the fluid to pass through a bypass line 23. A valve 24 in this line regulates the speed at which the fluid returns to the pressure source and therefore regulates the closing speed of the doors. It is apparent this valve 24 could be of other types than the needle valve shown and might be a spring loaded, normally closed valve which would hold the door open until released manually from within the garage.

The pressure supply system may be made in several different embodiments, several of which are shown in Figs. 2 through 6. In each it will be noted that there is a plurality of cylinder and piston assemblies, at least one piston of which is engaged before the others. More specifically, in the embodiment of Figs. 2 and 3, the pressure system comprises a base 27 on which are mounted the cylinders 28 and 29. The high pressure cylinder 28 is shown with a smaller diameter than the low pressure cylinder 29 although as previously described, they might well be of equal diameter. With the different diameters as shown, the ratio of the high pressure to low pressure will be greater than 2:1 which would be the ratio were the diameters equal. A high pressure piston 30 and a low pressure piston 31 are disposed in their respective cylinders 28 and 29; the operating rods 32 and 33 extending through the upper heads 34 and 35 of the cylinders. The cylinders 28 and 29 are connected to a common pressure line 36 which feeds into the supply line 21.

A lever 37 is hinged to the base 27 at 38 in position to engage the rods 32 and 33. This lever is formed such that in its downward travel it will engage the high pressure piston rod 32 sometime before the low pressure rod 33. Thus the high pressure piston 30 is forced down by the full weight on the lever 37 causing a high pressure in the line 36 and therefore in the actuating cylinder 11. The piston 31 is merely forced up against the upper head 35 during this part of the stroke. As the lever comes down because of the travel of the piston 15 in the actuating cylinder 11, it engages the rod 33 and then the force on the lever is balanced between two pistons of much larger area than the first one alone. As a result, the pressure is decreased, as described above, but the door will continue to open.

The force on the lever 37 is preferably the result of the weight of an automobile or other vehicle being driven onto the lever 37. To ac-

complish this, I provide ramps 40 adapted to be placed in one lane of a driveway. These ramps are pivoted to a platform portion 41 of the lever 37. Since the lever will necessarily tilt laterally about its hinge 38, it is desirable that the joint of the ramps 40 to the platform 41 be a universal swivelling joint. This may be any of several types of joints, but for this purpose, it is illustrated as a ball and socket joint 43. Rollers 44 may be provided pivoted to the lower end of the ramp 40 to allow the ramps to move longitudinally when the lever 37 moves downward.

The ramps preferably are of such length that the front wheels of an automobile will still be on one ramp when the rear wheels start onto the other. This will insure pressure on the lever 37 at all times during the passage of the vehicle and thus the length of time of continuous pressure to open the door will be greater.

The lever in this embodiment may be extended as shown to provide a foot pedal 47. This extension must be long enough so that a weight of approximately 100 pounds on it will open the door easily. It is then possible for the doors to be opened from the outside merely by stepping onto the foot pedal 47.

The parts are returned to their normal position by hydraulic action resulting from the return of the actuating piston 15 to its original position by the spring 19.

An alternative embodiment which will eliminate the need for the ball and socket joint 43 is shown in Fig. 4. In this embodiment the cylinders 28 and 29 are spaced longitudinally of the device rather than laterally; the high pressure cylinder 28 being placed under the ramp 40 first engaged by the vehicle's wheel. The platform 49 in this embodiment is supported by springs 50 at each of its corners. In order to prevent any except a vertical motion, sliding guides 52 are provided. These may well take the form of a telescoping rectangular box mounted on the platform 49, although the guides may not be necessary on the sides since there will be little lateral force. The ramps 40 in this embodiment are hinged to the platform 49 by a simple straight hinge 53 since the platform does not necessarily tilt laterally.

In operation this device is somewhat different from that previously described, although the principle is the same. In this embodiment, as the vehicle approaches and starts up the left hand (Fig. 4) ramp 40, the springs 50 on that side of the platform are compressed, and the ramp engages and forces downward the operating rod 32 of the high pressure piston 30. As the vehicle rolls up the ramp onto the platform 49, the springs on the other side of the platform are compressed and the low pressure cylinder and piston assembly are operated to provide the same result as in the prior embodiment. The piston rods 32 and 33 are necessarily placed close to the hinge points 43 and, therefore, the weight of the overhanging part of the ramp 40 is sufficient for keeping the ramp in contact with the ground instead of pivoting around the piston rod when the vehicle is on the platform 49 or the opposite ramp. A stop 54 is also provided to prevent too great force from being applied to the cylinders. This embodiment is returned to its original position primarily by corner springs 50 leaving only the pistons to be pushed up by the hydraulic system.

A third embodiment using concentric piston and cylinder means is illustrated in Fig. 5. In

this embodiment a large cylinder 53 is mounted on the base 54 to which the pressure line 21 is connected. A piston 55 is operably disposed in this cylinder and is held within the cylinder by a ring 56 fixed to the top of the cylinder by screws 57. While they are not shown, it will be understood by those skilled in the art that piston rings and packing glands or other types of sealing mechanism may be provided to prevent leakage of fluid from this cylinder.

A smaller cylinder 58 is formed in the piston 55 to provide the high pressure necessary for starting. A piston 59 having a stem or rod 60 is slidably disposed in the smaller cylinder with the rod extending through guide portion 62 formed in the large piston. A bar 63 extending laterally is fixed to the end of the rod 60 by some means such as welding. Ears 64 extending upwardly from this bar receive the pins 65 on which both ramps 40 may be pivoted in the well known manner of a hinge.

The operation of this embodiment is similar to that of those previously described. Since the ramps are hinged at a common line over the center line of the cylinders, there are no overhanging loads on the piston, and there will be, therefore, less tendency to binding of the piston in the cylinder. As the small piston reaches the end of its stroke, the bar 63 engages the top of the large piston 55 forcing it down with an effect exactly similar to the action of the two pistons in the prior described embodiments.

Still another embodiment is shown in Fig. 6. In the embodiment shown, the cylinder 67 is formed with a top 68 and guide portions 69, although these portions could be formed from a separate piece and attached to a cylinder similar to that of the embodiment just previously described.

The operating piston 70 in this cylinder has a 40 stem 71 slidably journaled in the guide 69. Above this, I have shown a necked-down section 72 extending upward to a small piston 73. A small cylinder 74 is slidably journaled on this piston 73 and carries a stop 75 fixed to the cylinder 74 and slidably journaled on the necked-down portion 72. It will be recognized that, if the small piston 73 were made somewhat larger than the stem 71, there would be no need for a necked-down section 72 as shown. A compression spring 76 may be disposed in the small cylinder 74 between the head 77 of the cylinder and the piston 73. This spring is held in a recess 78 in the cylinder so that before it is completely compressed, the cylinder presses on the piston to force the large piston 70 downward. A passageway 79 is formed through the pistons and their stems to connect the two cylinder chambers.

The head 77 of the small cylinder 74 may be formed with extensions thereon similar to the bar 63 of the previously described embodiment. Ears 64 holding the pin 65 on which the ramps 40 are journaled are exactly similar to those previously described.

The operation of this embodiment of pressure supply system is the same as that described above. As the liquid is forced through the passageway 79 into the tube 21 to the actuator, the cylinder 74 reaches the end of its travel and engages the stem of piston 70, forcing that piston downward with the same effect as previously described.

The application of my device to a lifting type gate is illustrated by Fig. 7. A gate 82 formed of a series of parallelograms having pinned, pivotal joints is hung on a post 83. The actuator as-

sembly of my device is also firmly mounted on this post. The cable 18, which is adapted to operate the gate 82, extends from the drum 17 over a pulley 84 at the top of the post 83 and is fastened at its other end to an eye 85 suitably fixed to the gate.

As the vehicle approaches the gate, the actuator is operated by the pressure supply system as previously described, and the cable 18 is wound on 10 the drum 17. This causes the gate to rise to the position shown by the dashed lines in Fig. 7. As the vehicle passes, the gate will close slowly at a rate dependent on the adjustment of the bleed valve 24 (Fig. 1). It is apparent that a pressure system could be put at both sides of the gate merely by using a T connection in the pressure line 21. This would make it possible to open the gate upon approaching from either direction.

A simple application of my device to an overhead garage door is illustrated in Figs. 8 and 9. The door 87 is hung from brackets 88 fixed to an axle 89. These brackets are preferably welded to the axle to prevent any relative motion therebetween. This axle is journaled at both ends in 25 a bearing carried by a housing 90 mounted on a bracket 91 which, in turn, may be fastened to the studdings or corner posts 92 on the inside of the garage. A pulley 93 is fixed to the axle 89 in a position where it may be operated by the actuator of my device. Since the door, and therefore the pulley, moves through only a quarter of a turn, it is apparent that a larger pulley can be used for cable operated doors.

I prefer this type of door because there is little 35 or no twisting strain on the door as it is being operated, all that strain being taken in the axle 89. However, this description is not to be interpreted as limiting the invention to applications of my device to this particular type of door. It 40 will also be apparent that, if a single device is not effective to open the door, a pair could be used simply by mounting the other actuator on the opposite side of the door and another pressure supply unit in the other runway of the drive. 45 However, for the ordinary usage, such double installation will not be required.

Other embodiments will be obvious to those 50 skilled in the art. For example, the cylinders might be placed individually in a staggered arrangement in a single path of the driveway, or preferably one in each path so that both would be operated at the same time, although the high pressure cylinder would be started first. It is 55 also apparent that more cylinders could be used provided the effect were the same.

Thus, it is apparent that I have provided a 60 door opener which is inexpensive and sturdy, requiring no auxiliary source of energy, and capable of opening a door or gate fully merely by the weight of an automobile.

Having thus described my invention, I am aware that numerous departures may be made therefrom without departing from the spirit or scope of my invention.

I claim:

Operating means for a hydraulic door opener comprising a base, a platform pivotally attached along one end to said base and having a portion extending over the base, the parts of which are 70 parallel to the base transversely of the platform, a plurality of cylinder means mounted on said base at different distances from the pivotal connection, the cylinder nearest the pivotal connection being of smaller diameter than the others, 75 pistons slidably disposed in said cylinders, oper-

ating means for said pistons adapted to be engaged successively by said platform in order of distance from said pivotal connection, and ramp means connected to said platform by a universal joint.
